HEAT EXCHANGE APPARATUS

John A. Potter and John P. Rathbun, Prospect Park, Pa., assignors to Westinghouse Electric & Manufacturing Company, East Pittsburgh, Pa., a corporation of Pennsylvania

Application April 17, 1933, Serial No. 666,580

9 Claims. (Cl. 257—239)

Our invention relates to surface type heat-exchange apparatus and it has for a broad subject to provide apparatus of this character which is of improved form and construction.

5 Apparatus of this character heretofore known to us usually comprises a tubular shell; a longitudinally-disposed nest of tubes in the shell; and a header construction at each end of the tube nest; each header including a tube sheet having 10 holes therethrough for receiving the ends of the tubes, a tubular body secured at one end to the tube sheet and a closure for the other end of the body.

Apparatus of this character is used to transfer 15 heat from one fluid to another fluid, one fluid flowing through the headers and the inside of the tubes, and the other fluid flowing through the shell and contacting with the exterior of the tubes. The heat exchanger may be either single pass or multiple pass, i. e., fluid may be caused to flow from one header and in one direction through all of the tubes to the other header, or the fluid may flow from one header through a portion of the tubes to the other header and 20 thence back through another portion of the tubes to the first header. Partitions are provided in the headers of multiple-pass heat exchangers to effect the desired character of flow of the fluid through the tubes. Also, if desired, either longitudinal or vertical baffles or both may be provided in the shell to effect any desired path of flow from the medium contacting with the exterior of the tubes.

The present invention has to do particularly 25 with heat exchangers wherein one or both of the fluids is under very high pressures, for example, a thousand pounds per square inch. In cases where only one of the fluids is under high pressure, that fluid is usually passed through the tubes, because it is cheaper to build a header construction to withstand a given high pressure than it is to construct a shell for such purpose.

In all headers, it is necessary to provide a removable end closure, so that the tubes may be cleaned or replaced. In prior types of high-pressure headers, end covers have been bolted to flanges provided on the outer end of the tubular body. However, considerable difficulty has been experienced with this construction due to the size of the flanges and bolts required to effect a seal against the high pressures of the fluid, and due to the difficulty in drawing the bolts down sufficiently tight to effect the seal and due to the difficulty in removing the bolts.

55 It has been proposed heretofore to eliminate

the large flanges and bolts by providing a self-sealing closure somewhat like a man hole cover. An elliptical opening is provided in the end of the header and an elliptical cover is provided having larger major and minor axes than the corresponding axes of the opening but having a smaller minor axis than the major axis of the opening. In assembling, the cover is turned endwise with its minor axis parallel to the major axis of the opening and in this relative position is inserted through the opening and then turned so that the corresponding axes of the cover and opening are parallel, and the cover is then drawn against the inside surface of the periphery of the opening with the peripheral surface of one side thereof engaging the surface of the cover about the opening and thereby effecting a complete closure of the opening. The pressure of the fluid within the shell will force the cover against the end and more effectively seal the opening. This type of construction, while it eliminates the necessity of large flanges and bolts and provides an effective closure, has the disadvantage of necessitating a relatively long tubular end to provide turning clearance for the elliptical cover plate in assembling. This construction also offers serious difficulties in installing transverse partitions in the header which as explained above are required in multiple-pass heat-exchangers.

The present invention has for an object to provide a new and useful high pressure header construction for heat exchangers which eliminates the necessity for large bolts and flanges; one which is self-sealing; one wherein ready access may be had to the tubes; and one wherein partitions may be readily installed in the tubular end.

These and other objects are effected by our invention as will be apparent from the following description and claims taken in connection with the accompanying drawings, forming a part of this application, in which:

Fig. 1 is a longitudinal vertical section showing heat-exchange apparatus constructed in accordance with the present invention, the section being taken on the line I—I of Fig. 2;

Fig. 2 is an end view of the apparatus shown in Fig. 1;

Fig. 3 is an enlarged fragmentary vertical section showing more clearly the construction of my improved high pressure header construction;

Fig. 4 is a detail view showing the end construction with the cover plates omitted;

Fig. 5 is a detail view of one of the cover plates;

Fig. 6 is a detail view of the spider-like holding means for the cover plates;

Fig. 7 is a view similar to Fig. 3 but on a smaller scale showing the manner of assembling the tubular body and end construction;

Fig. 8 is a view similar to Fig. 2 illustrating the manner of inserting the coverplate; and,

Fig. 9 is a detail sectional view similar to Fig. 7, but illustrating a modified form of header construction.

Referring now in detail to the construction illustrated, the reference numeral 10 indicates a tubular heat exchanger of the two-pass type, which comprises a cylindrical shell 11 closed at one end by a removable end cover 12 and closed at the other end by a header construction 13 bolted to a flange 14 carried by that end of the shell. A second header construction 15 is disposed in the closed end of the shell, and a plurality of fluid circulating tubes 16 extend longitudinally of the shell and connect the headers 13 and 15, the ends of the tubes extending through and secured within openings provided in the headers in a manner well understood to those skilled in the art. Longitudinal movement of the header 15 is not confined by the shell, the header 15 only being connected to the tubes 16. The purpose of this is to permit relative expansion of the tubes and shell and to permit withdrawal of the tubes and header through the shell for cleaning.

The header structure 13 comprises a cylindrical body 17, a tube sheet 18 formed integral with one end of the body 13, and an end construction 19 closing the other end of the body. A partition 20 may be disposed within the header to effect a multiple pass flow of fluid through the tubes, as will presently appear.

The end of the body 17 is provided with an integral circular flange 21 which is slotted at diametrically-opposed points as indicated at 22 in Fig. 7 to permit the insertion of the end construction 19 in assembling. The end construction 19 is a one-piece member comprising a ring portion 23 having a flange 24 engaging the inner side of the flange 21, the ring 23 and flange 24 being integrally joined to the body 17 by any suitable means, for example, welding as indicated at 25.

The end construction 19 is provided with a plurality of sector-shaped openings 26 having major and minor axes as indicated at 27 and 28, respectively (see Fig. 4). As will be observed from an examination of Fig. 2, the openings are shown as being of the same size and are disposed symmetrically about the central axis of the body 17. The openings 26 are sealed by cover plates 30 which are also sector-shaped as shown. The cover plates 30 also have major and minor axes 27a and 28b, respectively, which are larger than the corresponding axes 27 and 28 of their respective openings (see Fig. 5). The reason for this is to provide a sealing surface about the periphery of the cover plate 30 to effectively engage the inner surface of the end construction adjacent the openings and thereby effect a closure for each opening. The minor axis 28a of each cover plate is smaller than the major axis 27 of its respective opening so as to permit the cover plates to be inserted through the opening from the outside (see Fig. 8). In operation, the pressure of the fluid within the header construction 13 acts to force the cover plates 30 against the end construction 19 and thereby insure an effective closure for the opening.

As will be observed from an examination of Figs. 2, 3 and 4, the end construction 19 com-

prises radial portions 19a separating the openings 26. These radial portions increase in thickness from the periphery toward the center of the end construction and thereby provide an unusually strong truss structure for resisting internal pressures in the header 15.

The cover plates 30 are held in position with respect to their respective openings by means of a spider construction 31 comprising a central portion 32 having an opening 33 therethrough for receiving a bolt 34 which extends into a screw-threaded opening 35 in the central portion of the end construction 19, and a plurality of radially-extending finger portions 36 having openings 37 therethrough for receiving bolts 38 which are secured within screw-threaded openings 39 in the cover plates 30. A tightening of the bolts 38 clamps the covers against the end construction as will be readily appreciated.

In order to more effectively hold the covers in place, additional means in the form of a clamping ring 40 may be provided. As can be seen from an examination of Figs. 1 and 2, the clamping ring 40 is provided with a plurality of openings 41 which receive bolts 42, the latter extending into screw-threaded openings 43 provided in the cover plates 30 and, when drawn tight, serve as additional means for clamping the plates to the end construction.

As will be observed from an examination of Figs. 1 to 7, inclusive, the cylindrical body 17, tube sheet 18, and circular flange 21 are formed as a one-piece forging. The end construction 19 is also formed as a one-piece forging and is placed in position within the header 13 by turning edge-wise, as indicated in Fig. 7, and inserted through the slotted portions 22 of the flanges 21. After the end construction 19 is inserted slightly over halfway into the body 13, it may be turned transverse to the axis of the body and positioned against the inner surface of the flange 21. With the parts in this position, the end construction and body are integrally joined by welding, as before explained. Previous to the insertion of the end construction in the body, the partition plate 20 is placed in the body, and, after the end construction has been turned and welded in position, the partition 20 may be arranged in its proper position and securely welded to the adjacent surfaces of the body, end construction, and tube sheet.

A header construction so formed is extremely strong and will resist effectively unusually high pressures of the fluid therein. The engagement of the peripheral flange 24 of the end construction 19 with the inner surface of the flange portion 21 and the integrally joining of the body and end construction by welding, provides an unusually strong and rigid joint with no part of the weld under tension. The cover plates 30 having their peripheral surfaces engaging the inner surface of the end construction adjacent their respective openings, provide a self-sealing closure for the opening, that is to say, the high pressure of the fluid inside the header construction only acts to more effectively seal the openings by forcing the cover plate against the end construction. Suitable gasket means 40' may be provided between the overlapping surfaces of the cover plate and end construction to effectively seal the openings 26.

The partition 20 divides the header 13 into two chambers 45 and 46. An opening 47 is provided in the wall of the body 17 and communicates with the chamber 45, and a second opening 48 is pro-

vided in the body 17 and communicates with the chamber 46. The purpose of the openings 47 and 48 is to admit and discharge the fluid to be circulated through the tubes 16.

5 The header construction 15 is formed in identically the same manner as the header construction 13, the only difference being that it is smaller in diameter to permit its being removed longitudinally of the shell and that there are no inlet or outlet openings, nor is there a partition for dividing the header into different chambers. It is believed that a detail description of the header 15 is unnecessary in view of the previous description of the header 13.

16 In operation, either the fluid to be heated or to be cooled is admitted into the chamber 45 through the opening 47 and enters the ends of those tubes 16 communicating with this chamber and flows therethrough to the header 15 which 20 defines a chamber 49 communicating with the ends of all of the tubes 16. The fluid is returned through the remaining tubes to the chamber 46 in the header 13 and then conducted away from the apparatus through the opening 48. It is to 25 be observed at this point that, while we have shown a two-pass construction, it will be readily understood that by the provision of additional partitions in the header 13 and header 15, any 30 number of passes may be provided for the flow of fluid through the tubes.

The other fluid is admitted to the shell through an opening 50 and is discharged from the shell through an opening 51. A removable longitudinal baffle 52 provides for the flow of fluid from 35 the opening 50 lengthwise of the shell above the baffle, as viewed in Fig. 1, around the end of the baffle and thence longitudinally of the shell beneath the baffle and out the discharge opening 51. If desired, additional longitudinal baffles may be 40 provided for causing the fluid to pass longitudinally of the shell more times than just described, or transverse baffles may be provided for effecting a more intimate engagement of the fluid passing through the shell over the tubes. The additional longitudinal and transverse baffles are not 45 shown, but these and their functions are both well known in the art and further disclosure is deemed unnecessary.

In Fig. 9, we have illustrated a modified form of 50 header which comes within the scope of the present invention. The only difference between this header and the one previously described is that, instead of having a tube sheet formed as a single forging with the body of the header, it is formed 55 as a separate piece 60 and engages the inner surface of a flange 61 provided at the end of the header and is welded thereto. In Fig. 9, we have also indicated the manner of assembly of the end construction 63 and tube sheet 60 which is similar 60 to that described in connection with the end construction of the previous modification. As will be observed from an examination of this view, they are both inserted through slotted openings 64 provided in a flange 65 in the end of the body 65 opposite the shell. After insertion, they are turned, the tube sheet being arranged so that its outer periphery engages the surface of the flange 61 and is securely welded thereto. The end construction 63 is turned within the body and brought 70 back against the inner surface of the flange 65 and is welded thereto in the same manner as in the previous modification.

It is to be observed that, while we have shown 75 the sector-shaped openings 26 as being of the same size, insofar as the broader aspects of our

invention are concerned, they may be of different sizes. A construction may be designed wherein all of the cover plates 30 are inserted through one opening and afterwards positioned with respect to their respective openings. This, however, is only possible where the partitions provided in the header for defining separate chambers do not interfere with the positioning of the cover plates. In cases where only one partition is provided, as is shown in the preferred embodiment, the two openings at each side of the partition may be so arranged that the two cover plates can pass through one opening and then be positioned about their respective openings. With this in mind, it is to be understood that the invention in its broader aspects should only be limited to a construction wherein the axes of each cover plate are larger than the corresponding axes of their respective openings and one axis of each cover plate smaller than the major axis of one of the openings so that all the cover plates can at least be inserted through this one opening. It is preferred, however, that the cover plates be constructed in size and in the manner shown in the drawings so that the greatest degree of access may be had to the ends of the tubes.

It will be seen from the foregoing that we have devised an extremely strong header which will resist unusually strong pressures of the fluid passing through the tubes and at the same time have 105 devised a construction which eliminates the necessity of unusually large flanges and bolts for securing the end construction to the body and also does not necessitate an unusually long body construction to permit turning of the end construction and assembly. A further feature of our invention is that it readily adapts itself for multiple-pass heat exchanges in that the partitions may be placed in the header previous to assembly and, after the end construction is in position, integrally joined to the body by welding.

While we have shown our invention in two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

What we claim is:

1. In heat exchange apparatus, a header construction comprising a tubular body; a tube sheet rigidly fixed to one end of the body and having a plurality of holes therethrough for receiving tube ends; an end construction rigidly fixed to the other end of the body and having a plurality of sector-shaped openings therethrough distributed symmetrically about the central axis of the body; at least one of the openings having major and minor axes; a plurality of cover plates disposed within the body, there being one plate for each opening in the end construction and each cover plate being of such dimensions and so arranged with respect to its respective opening that the 140 surface of one side thereof adjacent its periphery engages the inner surface of the end construction adjacent the opening so as to effect a complete closure for the opening, the cover plate corresponding to at least said one opening having major and minor axes with its minor axis larger than the minor axis of said one opening, but smaller than the major axis of such opening, each of the remaining cover plates having axes larger than the corresponding axes of their re- 150

spective openings and at least one axis of each plate being smaller than the major axis of said one opening whereby all of the cover plates can be inserted through at least said one opening and at the same time the covers being of sufficient size to effect a closure for their respective openings; and means for holding the covers in position.

2. In heat exchange apparatus, a header construction comprising a tubular body; a tube sheet rigidly fixed to one end of the body and having a plurality of holes therethrough for receiving tube ends; an end construction rigidly fixed to the other end of the body and having a plurality of openings therethrough, each of which has major and minor axes; a plurality of cover plates disposed within the body, there being one plate for each opening in the end construction and each cover plate being of such dimensions and so arranged with respect to its respective opening that the surface of one side thereof adjacent its periphery engages the inner surface of the end construction adjacent its respective opening so as to effect a complete closure for such opening; each cover plate having major and minor axes and the minor axis of at least one of the covers being larger than the minor axis of its respective opening, but smaller than the major axis of such opening, and the minor axis of each of the remaining cover plates being larger than the minor axis of its respective opening and smaller than the major axis of the opening for said one cover whereby all of the cover plates can be inserted through the opening for at least said one cover plate and at the same time the cover plates being of sufficient size to effect a closure for their respective openings; and a common means for holding all of the cover plates in position about their respective openings.

3. Apparatus according to claim 1 wherein the tube plate and body are a single forging.

4. Apparatus according to claim 1 wherein the tube plate, body and end construction are integrally joined.

5. Apparatus according to claim 1 wherein the

tube plate and body are a single forging, and the end construction is of forged metal welded at its periphery to the end of the body.

6. Apparatus according to claim 1 wherein a common means is provided for securing all of the cover plates in position about their respective openings.

7. Apparatus according to claim 1 wherein a common means is provided for securing all of the cover plates in position about their respective openings, and said means comprises a spider construction including a center member secured to the center of the end construction at the outside thereof and arms radiating from the center member, there being an arm for each cover plate and each cover plate being held against the end construction by a bolt connecting such plate with its respective arm.

8. Apparatus according to claim 1 wherein the body and tube sheet are a single forging and an inwardly extending flange is formed integral with the body at the end opposite the cam, and the end construction engages the inner surface of the flange and is welded thereto.

9. In heat exchange apparatus, a header construction embodying a tubular body, a tube plate rigidly fixed to one end of the body, an end construction fixed to the other end of the body and provided with a circular series of openings affording access to the interior of the body and to the tubes, cover plates for the openings having boundary seating portions arranged to fit boundary seating portions formed at the inner side of the cover portion, said openings and cover plates being formed with major and minor axes with the minor axes of the cover plates less than the major axis of at least one of the openings, said openings being separated by radial portions of the end construction which increase in thickness inwardly and radially to provide a relatively stiff cover, and means for holding the cover plates in place with said seating portions engaged.
